UNITED STATES PATENT OFFICE.

GEORGE DUDLEY LOOMIS, OF TIFFIN, OHIO.

WELL-DRILLING MACHINERY.

SPECIFICATION forming part of Letters Patent No. 665,026, dated January 1, 1901.

Application filed June 17, 1899. Serial No. 720,953. (No model.)

To all whom it may concern:

Be it known that I, GEORGE DUDLEY LOOMIS, a citizen of the United States, residing at Tiffin, in the county of Seneca and State of Ohio, 5 have invented new and useful Well-Drilling Machinery, of which the following is a specification.

My invention relates to well-drilling machinery adapted particularly for operation by steam or horse power or other analogous power; and one object is to provide a simple, compact, and efficient machine which may be manufactured at a comparatively small cost and adaptable for spudding, as also for pipe-driving, with the minimum strain upon the supporting structure.

A further object of my invention is to provide a construction in which the drill will descend with much more rapidity than that with which it rises and in which this feature may be embodied in a machine employing a rope and a reciprocating beam for the reciprocation of the drill, and also one in which such reciprocation is secured by means of a walking-beam, this walking-beam being adapted for attachment to the spudding-beam interchangeably with the drill-rope, the method of attachment being such that both the drilling and the spudding operations may be performed without changing the direction of rotation of the driving-engine. This permits the employment of a single-acting engine and saves the expense of a reversible engine and the excessive work incident thereto. 35 A further object of my invention is to provide means for quickly throwing the drill-rope from the end of the spudding-beam to enable quick withdrawal of the drill, and also to simplify and perfect other specific portions 40 of the mechanism.

In the drawings forming a portion of this specification, and in which like numerals of reference indicate similar parts in the several views, Figure 1 is a detail perspective of my machine in readiness for the drilling operation and having the pitman connection between the spudding-beam and the lower beam omitted. Fig. 2 is a reverse view of Fig. 1 with the pitman connection between the beams in place. Fig. 3 is a longitudinal section on the line 3 3 of Fig. 4. Fig. 4 is a section on the line 4 4 of Fig. 1. Fig. 5 is a sec-

tion of one of the sliding bearing-blocks. Fig. 6 is a detail showing the eccentric bearing of the sand-drum. Fig. 7 is a detail of 55 the eccentric for sliding the bearings of the main drum. Fig. 8 is a detail of the mounting of the pulley upon the forward end of the spudding-beam. Fig. 9 is a detail showing a yieldable connection between the spudding-beam and the pitman which connects it with the lower beam.

Referring now to the drawings, in operating in accordance with my invention I form a body or base comprising side sills 1 and 2, 65 front and rear cross-pieces 3 and 4, and an intermediate cross-piece 5.

Extending upwardly from the forward ends of the sills 1 and 2 are uprights 5 and 6, having journals 7 in their upper ends adapted 70 to receive the trunnions 8 of a derrick, comprising sides 9 and 10, having the usual rungs 11, resulting in the formation of a ladder. The uprights 5 and 6 have suitable bracings 12, and transversely of the lower end of the 75 ladder is a cross-piece 13, the ends of which project to engage the adjacent faces of the uprights 5 and 6, and thus limit the forward movement of the lower end of the ladder and maintain it in an upright position. Other 80 and additional means of the usual form may be employed for holding the ladder in its elevated position.

Extending upwardly from the sills 1 and 2 a suitable distance from the derrick are uprights 14 and 15, having a shaft 16 passed horizontally therethrough, and which shaft carries the forked ends of a spudding-beam 17, having at its free end a pulley 18 upon a shaft 19, journaled in a stirrup. This stirrup 85 consists of a base 20, from one side of which is a vertical extension 21, extending beyond the upper periphery of the pulley 18, and then over and downward of the opposite face thereof, its lower end receiving the adjacent 95 end of the shaft 19. In order to prevent the derangement of the shape of this portion of the stirrup, I pivot to an ear 22, in alinement with the said downwardly-extending portion of the strip, an arm 23, having a slot 24 adjacent its upper end, and which slot receives the adjacent end of the shaft 19 when said arm is rotated upon its pivot to assume a vertical position. The slot 24 is directed toward

the end of the arm in order that it may not be displaced in the operation of the pulley.

Secured to the outer face of the arm 23 and extending parallel with the adjacent face of the pulley 18 is a rope-guard 25, which latter extends across the periphery of the pulley 18 and downwardly of the opposite side thereof to a point within the periphery of the pulley. This guard is separated from the face of the

10 pulley by a slight interspace to allow free rotation of the latter. A vertical perforation is made in the base 20 of the stirrup, and through this perforation is passed the threaded stem of a bolt 26, which is also passed 15 through an alining perforation in the spudding-beam 17. Withdrawal of the bolt 26 from said perforations is prevented through the medium of a nut 27 upon said bolt and engaging the upper face of said base.

20 In practice the drill-rope is passed around the pulley 18 and through the guard 25, the pivotal connection of the arm 23 permitting movement of the arm and guard to facilitate the application of the rope, after which the 25 arm is returned to engage the shaft 19 with the slot thereof. When the rope is to be disengaged from the pulley, the arm is moved pivotally to carry the guard rearwardly and the rope may be removed over the edge of the 30 pulley.

The opposite end of the bolt 26 is headed, and intermediate the head and the under side of the spudding-beam is a rubber washer 27^a, affording a yieldable connection between 35 the beam and the bolt-head.

30 From the under side of the head of the bolt 26 is extended a web, as shown, through which is formed a transverse perforation to receive the pivot of a pitman 28, for a purpose which will be presently described.

40 A supplemental sill 30 is arranged intermediate the sills 1 and 2, and on said sill 30 and the sill 1 are fixed bearings 31 and 32, which receive a shaft 33, carrying a gear-wheel 34. This gear-wheel, which is arranged 45 upon the shaft 33 beyond the sill 30, has upon its outer face a wrist-pin 35, upon which is mounted a roller 36, which fits snugly a longitudinal slot 37 in the lower beam 38 of my machine. This beam is formed of a T-iron, one end of which is bent in the plane of the web of the T in such manner that the flange of the bent-over portion will lie above and parallel with the flange of the adjacent portion of the body of the rail. At both extremities of the iron the web is removed, the extremity of the bent-over portion being bent downwardly and riveted or otherwise secured to the adjacent face of the flange of the body 50 portion. The flange at the opposite end of the iron is curved upwardly to form an eye, which eye 36^a is passed over the end of the shaft 37^a, as shown in Figs. 3 and 4 of the drawings, the shaft 37^a being journaled in 55 bearings on the sills 1 and 30 and parallel with the shaft 33.

The web of the bent-over portion of the T-

iron, from which the lower beam is formed, as above described, is provided with a series of perforations 39, adapted to receive the pin 70 at the lower end of a pitman 28, whose upper slotted end receives the web of the bolt 26 and to which web it is pivotally attached through the medium of a pin 41, passed through the arms of the pitman and the perforation in the web of the bolt-head. 75

The shaft 33 is what I term the "drive-shaft" and may have a universal connection, as shown at 42, with a shaft 43 leading to a common form of machine for utilization of 80 horse-power, or said shaft may be provided with a pulley-wheel adapted for the application of a belt from a steam-engine. It will thus be seen that as the shaft 33 is rotated the wrist-pin 35 will cause reciprocation of 85 the lower beam 38, and that as the wrist-pin in its upward movement operates upon the outer end of the beam it will raise the outer end with a quick motion, and that after said beam is raised it will be lowered with a slower 90 motion, due to the length of the path of the wrist-pin in its travel from the point of greatest elevation of the beam to the point of greatest depression. This is a result that has heretofore been secured through the medium 95 of cams, but with many resultant defects, all of which I overcome with this construction.

In the rear of the uprights 14 and 15 and parallel therewith are secured upon the sills 1 and 2 additional and shorter uprights 42 100 and 43, upon the upper ends of which are arranged horizontal beams 44 and 45, having blocks 46 and 47 secured upon their upper edges, in slidable engagement with which are bearing-blocks 48, in which is journaled a 105 shaft 49. Upon the shaft 49 is arranged a drum 50, and adjacent one end thereof and fixed to the shaft 49 is a friction-wheel 51, having a grooved periphery, as shown, which groove is adapted to receive a correspondingly-formed periphery of a second friction-wheel 52 upon the shaft 37^a, journaled in 110 bearings 54, fixed upon the sills 30 and 1, the shaft 49 and the parts carried thereby being adjustable with respect to the wheel 52 to 115 establish or destroy the frictional engagement between the wheels 51 and 52. Upon the shaft 37^a I arrange a sprocket 72, from which extends a sprocket-chain 73 to a second sprocket 74, arranged loosely upon the 120 shaft 33. A clutch 75 is splined to the shaft 33, as shown in Fig. 4 of the drawings, and is adapted to engage the adjacent faces of the sprocket 74, said clutch being adapted for reciprocation upon its shaft through the medium of a lever 75', having a spanner 76, whose inwardly-turned ends play in a peripheral groove in the clutch. Thus by manipulation of the lever 75' the sprocket 74 may be thrown into or out of engagement with its 125 shaft and cause the shaft 37^a to rotate and wind up its rope. 130

In order to reciprocate the shaft 49, and therewith the drum 50 and wheel 51, to cause

peripheral engagement of said wheel with wheel 52, I provide a rod 57, having a perforation at one end adapted to receive a portion of the bearing-blocks of the shaft 49, which projects beyond the main portion, said rod passing through a guide 58 upon the upright 15 and having at its opposite end an eccentric-strap 59, which lies upon an eccentric 60, carried by a shaft 61, journaled in a bearing 62 upon the sill 1. The shaft 61 has fixed thereto an operating-lever 63, through the medium of which said shaft and its eccentric may be rotated to reciprocate the rod 57 and shift the wheel 51 into or out of engagement with the wheel 52. The drum 50 is adapted to receive the drill-rope 64, which passes from said drum over a pulley 65, arranged loosely upon the shaft 16 in the uprights 14 and 15, thence into engagement with the under side of the pulley 18, and then upwardly and over the upper pulley of the derrick in the usual manner. Thus by manipulation of the levers 63 and 75 the drum may be caused to rotate either to withdraw the drill-rope or to allow it to pay out, and in order to hold the drum against rotation during the drilling operation a fixed brake-block 66 is fixed to the frame or body of the apparatus and has a curved face adjacent to the wheel 51 and into engagement with which face said wheel lies when at the limit of its rearward movement.

Mounted upon the braces 12 of the derrick are bearings 80, in one of which bearings is mounted a shaft 67, the other end of said shaft being mounted eccentrically of a cylindrical block 81, which in turn is journaled in the opposite bearing 80. This block 81 has a lever 82 extending therefrom in order that the adjacent end of said shaft 67 may be reciprocated for a purpose hereinafter explained. Upon the shaft 67 is a sand-drum 68, having thereon the usual rope 69. Upon the shaft 67 is also a friction-wheel 70, having a grooved periphery adapted to receive the correspondingly-formed periphery of a second friction-wheel 71 upon the shaft 37^b, when the shaft 67 and wheel 70 are shifted in the direction thereof, and upon said shaft 37^b is also disposed a pinion 56 in engagement with the gear-wheel 34 upon the shaft 33 and through the medium of which the friction-wheel 71 is rotated to rotate at times the drum 68.

The operation of my invention in this form will be readily seen upon inspection of Fig. 2 of the drawings and is as follows: The pitman 28 having been adjusted with respect to the lower beam 38 to secure the desired throw and the drill being in position, the shaft 33 is caused to rotate, causing a reciprocation of the beam 38 and a similar reciprocation of the spudding-beam 17, the drill being dropped with a sharp quick action and being withdrawn more slowly. It being then desired to withdraw the drill, the arm 23 of the stirrup

in which the pulley 18 is journaled is disengaged from the shaft 19, removing the guard 25 from the rope 64 and allowing its disengagement from the pulley 18. By manipulating lever 75' to engage the clutch with sprocket 74 shaft 37^a is caused to rotate, and by then drawing the lever 63 forward the friction-wheel 51 will be moved into engagement with the friction-wheel 52, when the drum 50 will be rotated and will wind in the rope 64, the pulley 65 lying inactive upon the shaft 16 as the rope is wound upon the drum. The rope from the sand-drum being unwound therefrom and it being desired to wind it thereupon, the lever 82 is operated to move the adjacent end of the shaft 67 in the direction of the friction-wheel 71, causing engagement of the peripheries of the wheels 70 and 71, the shaft 67 is rotated, and the drum 68 operated to wind its rope thereupon.

The utility of the washer 27^a (shown in Fig. 8 of the drawings) is particularly desirable in the employment of a wire cable in which there is practically no elasticity and without which washer the derrick and other portions of the mechanism would quickly succumb, it being evident, however, that I may omit the washer when this inelasticity is compensated for by other means; also, that I may employ a metallic spring in the place of the rubber washer.

As is well known, after the well-drilling operation has progressed to a certain point the spudding-beam can no longer be used, and when this is dispensed with I substitute therefor a walking-beam 90, having a pivotal connection with one of the rungs 91 of the derrick and equipped at its work end with the usual connections for engagement with the drill-rope, as shown in Fig. 2 of the drawings. The opposite end of the walking-beam is provided with a pitman 92, pivotally connected therewith, and which pitman is adapted for connection with the shaft 19, upon which the pulley 18 is normally mounted and from which said pulley may be removed to permit this connection. If desired, however, a single pitman may extend from the end of the walking-beam to the lower beam 38 and the spudding-beam thrown backwardly and out of the way. By this arrangement of walking-beam and spudding-beam the walking-beam may be connected with the spudding-beam interchangeably with the drill-rope to permit the operation of spudding or of drilling without changing the direction of movement of the rotating parts. This saves the expense of a reversing-engine, both as regards first cost and as regards maintenance and attention.

It will be readily understood that I may vary the specific construction and arrangement herein shown and described and that I may employ my form of spudding-beam in operative connection with a drilling-machine of other general construction and that other

means for throwing the parts into and out of gear may be employed without departing from the spirit of my invention.

Having thus described my invention, what I claim is—

1. A well-drilling machine comprising a frame including a derrick, a pulley for the derrick, a drill-rope passed over the pulley and adapted for operative connection with a spudding-beam pivoted in the frame, a second beam having a fixed relation to the spudding-beam, a rotatable body engaging the second beam and adapted to move longitudinally thereof to raise and lower it with varying speeds, and a pivoted walking-beam adapted for operative connection at one side of its pivot with the drill-rope and at the opposite side of its pivot with the second beam alternately with the operative connection of the drill-rope with the spudding-beam, whereby spudding or drilling may be performed with a quick down motion and a slower up motion and without changing the direction of rotation of the mechanism.
  2. A well-drilling machine comprising a frame including a derrick, a pulley for the derrick, a drill-rope passed over the pulley and adapted for operative connection with a spudding-beam pivoted in the frame, a second beam having a fixed relation to the spudding-beam, a rotatable body engaging the second beam and adapted to move longitudinally thereof to raise and lower it with varying speeds, means for varying the length of the arc of movement of the spudding-beam, and a pivoted walking-beam adapted for operative connection of one side of its pivot with the drill-rope and at the opposite side of its pivot with the second beam alternately with the operative connection of the drill-rope with the spudding-beam, whereby spudding or drilling may be performed with a quick down motion and a slower up motion and without changing the direction of rotation of the mechanism.
  3. In a drilling mechanism, the combination with a spudding-beam and a drill-rope adapted for operative connection therewith, of a second beam connected with the spudding-beam, means for raising and lowering the second beam and therewith the spudding-beam at different speeds, and a pivoted walking-beam adapted for connection at one side of its pivot with the spudding-beam and at the opposite side of its pivot with the drill-rope alternately with the connection of the drill-rope with the spudding-beam, whereby spudding or drilling may be performed with a quick down motion and a slower up motion and without changing the direction of rotation of the mechanism.
  4. In a well-drilling machine, the combination with the derrick and its supporting-frame, of a spudding-beam pivotally connected with the frame, a pulley concentric with the fulcrum of the beam, a second pulley upon the outer end of the beam, a drum
- upon the frame, a rope upon the drum adapted for operative engagement with said pulleys and the derrick, a lower beam operatively connected with the spudding-beam, a yieldable cushion between the beams, means for operating the lower beam with a quick up motion and a slower down motion, and a walking-beam pivoted in the derrick and adapted for connection with the spudding-beam at one side of its pivot and with said rope at the opposite side of its pivot alternately with the engagement of the rope with the spudding-beam, whereby drilling or spudding may be performed with a quick down motion and a slower up motion and without changing the direction of rotation of the mechanism.
5. In a well-drilling machine, the combination with a derrick and its supporting-frame, of a drill-rope depending from said derrick, a spudding-beam, a slotted lever pivoted to the frame and having connections with the spudding-beam, a drill-rope adapted for yieldable connection with the spudding-beam, a wheel adjacent the lever and having a projection lying in the slot of the latter and adapted to move longitudinally thereof to raise and depress the lever with a quick up motion and a slower down motion, means for operating the wheel, and a walking-beam pivoted in the derrick and adapted for connection with the spudding-beam at one side of its pivot and with the said rope at the opposite side of its pivot alternately with the engagement of the rope with the spudding-beam, whereby spudding or drilling may be performed with a quick down motion and a slower up motion and without changing the direction of rotation of the mechanism.
6. In a drilling mechanism, the combination with a spudding-beam of a guide-pulley, a frame for the pulley mounted at the free end of the beam, said frame having a movable portion adapted to open the frame and permit the application and removal of the drill-rope and a guide fixed to the movable portion to bridge the wheel when the movable portion is in its closed position, a derrick, a drill-rope slidably engaged with the derrick and adapted for engagement with the guide-pulley, a second beam connected with the spudding-beam, means for lowering and raising the second beam to correspondingly move the spudding-beam at different speeds, and a pivoted walking-beam adapted for connection at one side of its pivot with the spudding-beam and at the opposite side of its pivot with the drill-rope alternately with the connection of the drill-rope with the spudding-beam, whereby spudding or drilling may be performed with a quick down motion and a slower up motion and without changing the direction of rotation of the mechanism.
7. In a well-drilling machine, the combination with a spudding-beam, of a guide-pulley at one end thereof, a supporting-frame for said pulley, said frame having a movable portion adapted to open the frame to permit the

application and removal of the drill-rope, and a guide fixed to the movable portion and adapted for movement therewith into and out of operative relation to the pulley to permit application of the drill-rope to and removal from the pulley.

8. In a drilling-machine, the combination with a spudding-beam of a guide-pulley yieldably connected therewith, a drill-rope engaged with the pulley, a second beam connected with the spudding-beam, means for raising and lowering the second beam and therewith the spudding-beam at different speeds, and a pivoted walking-beam adapted for connection at one side of its pivot with the spudding-beam and at the opposite side of its pivot with the drill-rope alternately with the connection of the drill-rope with the spudding-beam, whereby spudding or drilling may be performed with a quick down motion and a slower up motion and without changing the direction of rotation of the mechanism.

9. In a drilling mechanism, the combination with a derrick having a guide-pulley, of

a drill-rope passed over the pulley and adapted for operative connection with a pivoted spudding-beam, a second beam having a fixed relation to the spudding-beam, a wheel having a connection with the lower beam and adapted to move it upwardly and downwardly with varying speeds, means for varying the arc of movement of the spudding-beam, a walking-beam pivoted to the derrick and adapted for operative connection at one side 30 of its pivot with the drill-rope and at the opposite side of its pivot with the second beam alternately with the operative connection of the drill-rope with the spudding-beam, a sand-drum at the base of the derrick and 35 between it and the wheel which operates the spudding-beam, and means for operatively connecting the sand-drum with said wheel.

In testimony that I claim the foregoing as my own I have hereto affixed my signature 40 in the presence of two witnesses.

GEORGE DUDLEY LOOMIS.
